W. R. MCCLURE

SHOE FASTENER

Filed May 28, 1928

William R. McClure
Inventor

By *Cadhow & Co.*
Attorneys.

UNITED STATES PATENT OFFICE.

WILLIAM RANDALL MCCLURE, OF CHICAGO, ILLINOIS.

SHOE FASTENER.

Application filed May 28, 1928. Serial No. 281,161

This invention relates to a device to be used more particularly with oxfords of the blucher type, the primary object of the invention being to provide means for securing the upper of the oxford closed, in place of the usual and well known shoe string.

An important object of the invention is to provide a securing device of this type which will hold the edges of the upper of the oxford closed at all times, eliminating any possibility of the shoe becoming loose on the foot of the wearer.

A still further object of the invention is the provision of a device which may be readily and easily secured in position.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a view illustrating the application of the securing device.

Figure 2 is a sectional view taken on line 2-2 of Figure 1.

Figure 3 is a perspective view of one of the hook carrying bars of the fastener.

Figure 4 is a perspective view of the bar associated with the hook carrying bar shown by Figure 3.

Figure 5 is a perspective view of the hook carrying bar at the opposite side of the fastener.

Figure 6 is a longitudinal sectional view through the center portion or springs of the fastener.

Referring to the drawing in detail, the device embodies a hook carrying bar 5 to which the hooks 6 are secured, the hooks extending downwardly and laterally in a manner as shown by Figure 2 of the drawing. This bar is provided with openings 7 arranged between the hooks 6, which openings receive the hooks 8 of the coiled springs 9, securing the coiled springs to the bar 5.

The hooks 6 are so constructed that they will readily fit within the eyelets of the upper of the oxford to take the place of the usual shoe lace. The opposite ends of the springs 9 are provided with hooks 10 that hook into

openings 11 of the bar 12 which is formed with notches 13 adjacent to its ends and extending inwardly from the inner edge of the bar.

Associated with the bar 12 is a bar 14 to which the hooks 15 are secured, the hooks 15 being of a construction identical with the hooks 6 and designed to pass into the eyelets of the shoe upper, at the opposite side of the shoe opening. Extending upwardly from the bar 14 are headed pins 16 that fit within the notches 13 to removably secure the bars 12 and 14 together with the result that when the device is secured to the shoe upper the bar 12 may be readily and easily connected or disconnected from the bar 14 by moving the bar 12 away from the pins 16.

As clearly shown by Figure 6 the spring coils are oval in cross section so that they will lie flat and will not extend to such positions that they will bind the instep of the wearer.

It might be further stated that the hooks 6 and 15 are of such lengths that they will lie between the upper of the shoe and the tongue which is indicated by the reference character 17.

From the foregoing it will be obvious that when a fastening device of this type has been secured to a shoe, the bar 12 may be readily and easily moved into and out of engagement with the pins 16 of the bar 14 to permit the shoe to be readily and easily opened or closed.

It will further be seen that the upper of the shoe will be held in a predetermined position at all times, and that there will be a certain amount of give when the foot is bent in the usual way when the person is walking, thereby insuring against the fastener binding over the instep.

I claim:

1. A shoe fastener of the class described including a bar having hooks to be positioned in the eyelets of a shoe upper, a bar having hooks positioned in the eyelets at the opposite side of the shoe upper, coiled springs connected with the first mentioned bar, a movable bar connected with the springs, and means for detachably connecting the second mentioned bar and movable bar.

2. A shoe fastener of the class described including a bar, hooks extending from the bar and adapted to pass into the eyelets of a shoe upper, a bar having hooks positioned in the eyelets at the opposite side of the shoe upper, a bar removably connected with the

second mentioned bar, and resilient means for connecting the first mentioned bar and latter bar.

3. A shoe fastener of the class described including a bar, means on the bar and extending into the eyelets at one side of the shoe to removably secure the bar in position, a bar

removably secured at the opposite side of the shoe, and coiled springs connecting the bars and overlying the instep, to connect the bars. 10

In testimony that I claim the foregoing as my own, I have hereto affixed my signature.

WILLIAM RANDALL McCLURE.
